UNITED STATES PATENT OFFICE

MATTHEW F. BAYER, OF KENOSHA, WISCONSIN, ASSIGNOR TO SIMMONS COMPANY, OF KENOSHA, WISCONSIN, A CORPORATION OF DELAWARE

MATTRESS AND LIKE STRUCTURE

Application filed June 13, 1924. Serial No. 719,726.

My present invention, while susceptible of wider application, is especially applicable to that class of mattresses or cushions the resiliency of which is secured by means of coil springs inclosed within a casing and ordinarily surrounded by a pad secured to the casing walls. In mattresses and like structures of this character, it is highly important that the coil springs shall be united together in such manner that while the greatest flexibility is obtained, the danger of the springs chafing together and becoming distorted shall be avoided. The invention is directed primarily to the provision of improved means for holding the springs in proper and most effective relative position, and the invention consists in the features of novelty hereinafter described, illustrated in the accompanying drawings and particularly pointed out in the claims at the end of the specification.

Figure 1 is a plan view showing a group of springs embodying my invention. Figure 2 is a view in vertical section through a mattress or cushion embodying the invention. Figure 3 is a view in vertical section on line 3—3 of Fig. 4. Figure 4 is a detail plan view showing the improved manner of connecting adjacent coil springs together. Figure 5 is a view in cross section on line 5—5 of Fig. 4. Figure 6 is a detail view of a metal fastener used in carrying out my invention.

The coil springs A will be arranged in rows and are shown as inclosed within a casing B of ticking or like material that may be surrounded by a pad C, this pad being united to the casing as by tufting cords D, corner threads D', etc., in a manner well understood by those familiar with this class of devices.

The terminal coils of each of the springs A is formed with offset portions a arranged at diametrically opposite points, as clearly shown in Fig. 1 of the drawings. These terminal coils of the springs A, when placed in juxtaposition, are united together by flexible connections E of fibrous material extending between said springs. Preferably, the connections E consist of spiral strands e and e' of heavy cord, the end portions of these strands being connected to the terminal coils

of the springs A by means of metal fasteners F. Each of these fasteners F is formed with a plurality of arms f, f' and f'', the arm f being, by preference, of somewhat greater width than the arms f' and f''. In fastening the terminal coils of adjacent springs together, the strands of the flexible connections will be laid across the offset portions a of the terminal coils of the springs A. The metal fasteners F will be placed about the strands of the flexible connections in such manner that the broad arm f of the fastener F shall extend between the ends of the strands e and e' and upon the inside of the offset portion a of the terminal coil, while the arms f' and f'' of the fastener F extend upon the inside of the coil preferably adjacent the juncture of the inclined portion a' of the offset a with the body of the terminal coil of the spring A. The arms f, f' and f'' of the fastener F will be bent around the inclined portions a' of the offset a, as shown in Figs. 3 and 4, and the arm f of the fastener F will be bent inwardly as shown, the fastener F thus rigidly uniting the flexible strands to the terminal coil of the spring and in such manner that all danger of the pulling of the strands from the fastener is avoided. Inasmuch as the crown of the fastener F extends across the offset portion a of the terminal coil, while the arms of the fastener are rigidly clamped or clenched in the position shown, all danger of any vertical or circumferential movement of the fastener is avoided. At the same time, however, the strands e and e' afford a flexible connection between the terminal coils of the adjacent springs, thus giving a far greater uniformity of elasticity to the spring structure as a whole than would be possible if the springs were rigidly connected together. The flexible connections while serving to yieldingly unite the spring coils, effectively hold them in proper relative position in a manner permitting a great uniformity of elasticity and without danger of the springs chafing together or becoming interlocked.

It will be observed that the strands are relatively thick and stout, with their intermediate unclamped portions relatively short,

so that they operate not only as ties for preventing separation of the coils, but also as struts for preventing the springs from approaching each other close enough for the offsets or clips to make contact with each other.

The individual "action" of each spring is thus preserved to the maximum extent possible, while at the same time the spring assembly is sufficiently rigid to keep the construction of the desired shape and size during assembly and also in service.

Since the specific embodiment herein disclosed is merely illustrative of a single application of my invention, it will be understood that the scope of same should be determined by reference to the appended claims, said claims being construed as broadly as possible, consistent with the state of the art.

Having thus described my invention, what I claim as new and desire to secure by Letters Patent is:—

1. A mattress or like structure comprising a plurality of rows of coil springs arranged in juxtaposition with their axes parallel, relatively short stout connections of flexible fibrous material extending between the end coils of adjacent springs and metallic fasteners rigidly united to said springs and rigidly securing said connections to the respective springs, the intermediate portions of said connections serving as hinges, as ties, and also as compression members for preventing metal to metal contact between adjacent metal parts associated with said compression members.

2. A mattress or like structure comprising a plurality of rows of coil springs arranged in juxtaposition with their axes parallel and means for preventing metal to metal contact between adjacent springs, tying said springs together while providing for the necessary flexibility of the structure as a whole, comprising offset portions formed in the end coils of adjacent springs, relatively short, stout, fibrous cords extending between the respective offset portions, and metallic fastening clips for the adjacent offsets, each embracing its respective offset and an end of said cord and clamping the clip itself and said cord end rigidly to said offset, the clip being so interlocked with said offset and end coil as to prevent movement of the clip around the wire of the end coil and along the wire of the end coil.

3. A mattress or like structure comprising a plurality of rows of coil springs arranged in juxtaposition with their axes parallel, double connections of flexible fibrous material extending between the end coils of adjacent springs, and metallic fastener clips rigidly united to said springs and rigidly securing said connections to the respective springs, said end coils having offset portions including, in effect, a pair of arms respectively extending angularly from the adjacent portions

of the respective end coils, and the end portions of said double connections being respectively secured to said arm portions by said clips.

4. A mattress or like structure comprising a plurality of rows of coil springs arranged in juxtaposition with their axes parallel, double connections of flexible fibrous material extending between the end coils of adjacent springs, and metallic fastener clips rigidly united to said springs and rigidly securing said connections to the respective springs, said end coils having offset portions including, in effect, a pair of arms respectively extending angularly from the adjacent portions of the respective end coils, and the end portions of said double connections being respectively secured to said arm portions by said clips, the latter comprising, in effect, three-armed members, two of the arms of which serve respectively to secure said connections to said offset end coil arms, and the third arm of said clip serving to bite into said connections to prevent slippage thereof with respect to the springs.
